INVENTOR
CHARLES C. THOMPSON
BY
Frank L. Graham
ATTORNEY

UNITED STATES PATENT OFFICE.

CHARLES C. THOMPSON, OF GLENDALE, CALIFORNIA.

REINFORCED ADOBE BLOCK AND WALL CONSTRUCTION.

Application filed August 24, 1925. Serial No. 51,998.

As may be inferred from the above title, this invention relates particularly to the re-enforcement of blocks, such as adobe blocks, adapted to be used in the construction of walls, such as, for example, the walls of dwellings; and this invention includes also the resultant reenforced walls, and means and methods for the production of the mentioned blocks and walls.

10 By reason of the ready availability of suitable materials and labor for adobe construction, and the comparative rarity and expense of more durable materials, and the comparative rarity of rains in certain sections, adobe 15 comprising a natural clay admixed with straw and molded into blocks, has been extensively used in the Pacific southwest, and elsewhere; and walls formed from adobe blocks have many advantages, when the 20 blocks are properly formed and laid and protected; but, as heretofore formed, they are poorly adapted to withstand oscillatory movements such as are characteristic of 25 earthquake shocks; and it is an object of this invention to provide blocks and walls which, even when made of the comparatively inexpensive material mentioned, shall be little liable to the cracking and disintegrating effects 30 of seismic disturbances.

30 It is an object of this invention to provide building blocks with reenforcement extending diagonally therethrough and optionally projecting from one or both ends thereof; and preferred embodiments of this invention may 35 comprise wire mesh reenforcements adapted not only to resist fracture of the individual brick but to extend between the bricks of successive corners in such manner as to bond the blocks together and give the resultant wall a 40 degree of tensile strength.

Other objects of my invention, including the optional employment of reenforcement extending from a lateral surface or surfaces of blocks and adapted to contribute to the 45 bonding of a protecting coat thereto, may be best understood from the following description of alternative embodiments thereof, taken in connection with the appended claims and the accompanying drawings, in which

50 Fig. 1 is a perspective view of one advantageous form of block illustrating my invention.

Fig. 2 is an elevational view of a slightly different type, in which the reenforcing web 55 extends more exactly through diagonally opposite horizontal edges of a block.

Fig. 3 may be regarded as a vertical section through a wall comprising blocks of the general type illustrated in Fig. 2.

Fig. 4 is a top plan view of a partially completed wall, showing how the described blocks may be used at corners and near openings, and how the projecting reenforcement may be used not only to strengthen the introduced blocks but to bond the same together and to 60 anchor a protecting coat thereto.

Fig. 5 is a plan view or horizontal section comparable with a part of Fig. 4, but showing a thinner wall as formed of blocks from which the reenforcement projects laterally in such 70 manner as to enter a protecting coat laterally applied.

As shown, each of my adobe or other blocks 11, 11^a, 11^b comprises a web or mesh reenforcement 12 extending diagonally therethrough, 75 the essential difference between the block shown in Fig. 1 and the blocks shown in Figs. 2 and 3 being that, in the latter, the reenforcement is intended to emerge as nearly as may be from the respective upper and lower horizontal edges of the ends thereof, whereas, in the former, in order to diminish the liability to fracture, the reinforcing web emerges near said edges but at short distances above and below the same.

Blocks of the general character described may be quickly and conveniently made in any preferred manner such as by means of a mold or form.

In the use of my novel reenforced blocks, 90 the projecting portions 17 thereof may be bent into horizontal planes so as to become engaged between superimposed courses of like bricks, substantially as shown in Fig. 3; and at the ends of courses, as at corners or openings in walls, and even when blocks are shortened, instead of cutting off the projecting portions 17, 17^a of reenforcement, the same may be bent down and used as a means for the 95 secure attachment of a waterproof or other coating, such as, for example, a Portland cement mixture applied to one or both surfaces of a wall.

Thus the projecting ends of my diagonal reenforcing members may be used not only to strengthen the individual blocks and to impart a degree of tensile strength to a block wall but to bond a protecting or finishing coat thereto and to protect exposed corners and edges; and, if desired, the described reenforcing members, or their equivalents, may be of such width as to project laterally be-

yond the vertical surfaces of my blocks, somewhat as suggested at 18, Fig. 5, in order to provide additional anchorage for the coating 19.

5 Although I have herein described a single complete embodiment of my invention, it will be understood that various features thereof might be independently employed; and also that numerous modifications thereof might 10 be devised, by those skilled in the art to which this case relates, without the slightest departure from the spirit and scope of this invention as the same is indicated above and in the following claims.

15 I claim as my invention:

1. A substantially vertical wall comprising: self-supporting blocks superimposed, one upon the other in substantially parallel rows and disposed with their largest surfaces 20 in substantially horizontal planes; said blocks being diagonally reenforced with metallic

mesh which projects from diagonally opposite edges of said blocks and the projecting sections of which are embedded between superimposed horizontal courses of like 25 blocks.

2. A substantially vertical wall comprising: self-supporting blocks superimposed, one upon the other in substantially parallel rows and disposed with their largest surfaces in substantially horizontal planes; said blocks being diagonally reenforced with metallic mesh which projects from diagonally opposite edges of said blocks and the projecting sections of which are embedded between superimposed horizontal courses of like blocks,— 30 said metallic mesh also projecting laterally from said blocks into a protecting coat.

In testimony whereof, I have hereunto set my hand at Los Angeles, California, this 18th 40 day of August, 1925.

CHARLES C. THOMPSON.
